His Attorney

UNITED STATES PATENT OFFICE.

HERMAN G. BLOSSER, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 8, 1924, Serial No. 634,962. Renewed January 23, 1926.

To all whom it may concern:

Be it known that I, HERMAN G. BLOSSER, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic 10 controlling apparatus, and particularly to apparatus of the type comprising loop circuits or local circuits for the control of train carried governing means.

I will describe one form of trackway 15 apparatus embodying my invention, and will then point out the novel features thereof in claims.

The accompanying drawing is a diagrammatic view showing one form of trackway 20 apparatus embodying my invention.

Referring to this drawing the reference characters 1 and 1^a designate the track rails of an electric railroad. Parallel with these track rails is a third rail or trolley 6. An 25 impedance 5 is connected across the rails of the stretch, and alternating propulsion current is supplied to the rails through impedance 5 and to the trolley 6 from some suitable source as an alternator E. The 30 track rails 1 and 1^a are divided, by means of insulating joints 2, into a plurality of successive track sections A—B, B—C, C—D, etc.

Propulsion current is conducted past each 35 pair of insulated joints by an impedance bond H. Referring particularly to the impedance bond located at point B, this bond comprises two impedances 3 and 3^a connected across the right hand end of section A—B and the left hand end of section B—C, respectively. The mid points of 40 these two impedances are connected together by a conductor 4 in the usual manner.

Each track section is provided with a loop 45 circuit over which loop current flows to control traffic through the stretch in any desired manner. This loop current is supplied from loop transformers designated by the reference characters T with appropriate 50 distinguishing exponents. The primary 8 of each such transformer T is constantly supplied with alternating current of a fre-

quency different from the frequency of the propulsion current from an alternator G over line wires 7 and 7^a. 55

Referring particularly to section A—B, the loop circuit for this section passes from secondary 10 of loop transformer T^b, through wire 21, impedance 20, wire 19, primary 11 of an auxiliary transformer K², 60 wires 18, 17 and 4, impedance 3^a at point A, through the rails of section A—B in parallel, to impedance 3 at point B, and wires 4, 16 and 15 back to secondary 10 of transformer T^b. The loop circuit for 65 section B—C may be traced from the secondary 9 of transformer T^b, through wire 27, impedance 26, wire 25, primary 11 of auxiliary transformer K³, wires 24, 23 and 4, impedance 3 at point C, through both 70 rails of section B—C in parallel to impedance 3^a at point B, thence by wires 4, 16 and 22 back to secondary 9 of transformer T^b. 75

The purposes of impedances 20 and 26 is to regulate the amount and phase of loop current in the associated circuits.

Under certain conditions of operation the propulsion current flowing in the rails creates a potential difference between the 80 ends of the track sections. This potential difference, in the absence of any preventative means may result in an excessive current through the loop circuit which current may destroy the impedances 20 and 26 and 85 the windings 9 and 10 of transformers T. To prevent such occurrence I tune the secondary winding 12 of each auxiliary transformer K to approximate resonance at the 90 frequency of generator G by means of a reactor 13 and a condenser 14. It follows that the transformers K will offer comparatively small impedance to loop currents, but that propulsion current flowing in the 95 loop circuits is opposed by a comparatively high impedance. As a result the propulsion current through the loop circuits is reduced to a comparatively low value.

The small amount of propulsion current 100 which does flow in the loop circuits is prevented from feeding back into line wires 7 and 7^a by reversing the connections of the local transformer secondaries for adjacent sections. Thus local current for sec-

tion B—C flows through secondary 9 of transformer T^B in one direction and the local current for section A—B flows through secondary 10 of this transformer in the other direction. These two currents balance each other and therefore the feed back of propulsion current to the signal line wires is prevented.

Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what I claim is:

1. A railway traffic controlling apparatus comprising a stretch of railway track, a loop circuit including the two rails of the stretch in multiple and a source of alternating current, and means associated with said circuit responsive to the frequency of the current supplied thereto.

2. Railway traffic controlling apparatus comprising a stretch of railway track having propulsion current flowing therein, a loop circuit including the two rails of the stretch in multiple, and frequency responsive means associated with said loop circuit for preventing the flow of propulsion current in said circuit.

3. Railway traffic controlling apparatus comprising a stretch of railway track having alternating propulsion current of one frequency flowing therein, a loop circuit including the two rails of the stretch in multiple and a source of alternating current of a different frequency, and frequency responsive means associated with said circuit for preventing current of the frequency of said propulsion current from flowing in said loop circuit.

4. Railway traffic controlling apparatus comprising a stretch of railway track having alternating propulsion current of one frequency flowing therein, a loop circuit including the two rails of the stretch in multiple and a source of alternating current of a different frequency, and means associated with said loop circuit for offering a high impedance to said propulsion current but for offering a low impedance to current from said source.

5. Railway traffic controlling apparatus comprising a stretch of railway track having propulsion current flowing therein, a loop circuit including the two rails of the stretch in multiple, a loop transformer for supplying alternating current to said loop circuit, and frequency responsive means for preventing the flow of propulsion current through said transformer.

6. In combination, a stretch of railway

track, a loop circuit for said stretch including the two rails of the stretch in multiple and a source of alternating current, and a transformer having one winding included in said loop circuit and a second winding 70 tuned to approximate resonance at the frequency of said source.

7. Railway traffic controlling apparatus comprising a plurality of successive sections of railway track, a loop circuit for each section including the two rails of the section in multiple, a source of energy for supplying alternating loop current to each said section, and a transformer for each section having one winding included in the corresponding loop circuit and a second winding tuned to 75 approximate resonance at the frequency of the loop current supplied to said circuit.

8. Railway traffic controlling apparatus comprising a forward and a rear section of railway track, means for supplying propulsion current to the rails of said sections, a loop circuit for each said section including at least one rail of the associated section, means for supplying alternating loop current of one relative polarity to one such loop circuit and for supplying alternating loop current of the other relative polarity to the other loop circuit, and frequency responsive 80 means for each said loop circuit for preventing propulsion current from flowing in such circuit.

9. In combination, two successive sections of railway track, and means for causing alternating train controlling loop current to flow in the two rails in multiple of each section in such manner that at any given instant the directions of flow in the two sections are opposite.

10. In combination, two successive sections of railway track carrying alternating electric propulsion current, a train control transformer having a primary supplied from an alternating current transmission line and two secondaries, and a loop circuit for each section including the rails of the section in multiple and one of said secondaries, the secondaries being so connected that at any given instant the directions of flow of loop current in the two sections are opposite 105 whereby equal amounts of propulsion current flowing in said two loop circuits will have equal and opposite effects on the primary of said transformer and so will create 110 no flow of propulsion current in said transmission line.

11. In combination, two successive sections B—C and C—D of railway track, an impedance connected across the track rails of each section at each end of the section, a train control transformer having a primary supplied with alternating current and two secondaries, means for connecting two like terminals of said two secondaries with the two impedances adjacent the junction of 125 130 135

said sections, and means for connecting the other two secondary terminals with the other two impedances respectively.

12. In combination, two successive sections of railway track, a train control transformer having a primary supplied with alternating current and two secondaries, and loop circuits for said sections including the track rails in multiple and said two secondaries respectively, said secondaries being so connected that at any given instant the directions of flow of loop currents in the two sections are opposite.

13. In combination, two successive sections of railway track, a train control transformer having a primary supplied with alternating current and two secondaries, and means including said secondaries for supplying loop currents of opposite instantaneous relative polarities to said two track sections.

14. In combination, two successive sections of railway track carrying alternating electric propulsion current of one frequency, a transformer having a primary supplied from a transmission line carrying train control current of a different frequency, said transformer having two secondaries, and means including said secondaries for supplying loop currents of opposite instantaneous relative polarities to said two track sections.

15. In combination, two successive sections of railway track carrying alternating electric propulsion current of one frequency, a transformer having a primary supplied from a transmission line carrying train control current of a different frequency, said transformer having two secondaries, means including said secondaries for supplying loop currents of opposite instantaneous relative polarities to said two track sections, and frequency responsive means associated with the loop circuit of each section for freely transmitting train control current but opposing the flow of propulsion current.

16. Railway traffic controlling apparatus comprising a stretch of railway track having propulsion current flowing in the rails

thereof, a loop circuit including the two rails of the stretch in multiple and a source of loop current, and means tending to prevent propulsion current from flowing in said loop circuit.

17. Railway traffic controlling apparatus comprising a stretch of railway track having propulsion current flowing in the rails thereof, a loop circuit including the two rails of the stretch in multiple and an impedance element, and means for reducing the impedance of said element to loop current but not to propulsion current.

18. Railway traffic controlling apparatus comprising a stretch of railway track having propulsion current flowing therein, a local transformer, a loop circuit including the two rails of said stretch in multiple and a winding of said transformer, and means for preventing the flow of propulsion current in said transformer.

19. In combination, a plurality of successive sections of railway track having propulsion current flowing therein, impedance bonds for conducting propulsion current from each section to the adjacent sections, a loop circuit for each section including the two rails of the section in multiple and an impedance, and means associated with each such circuit for preventing the flow of propulsion current through such impedances.

20. In combination, a plurality of successive sections of railway track having propulsion current flowing therein, impedance bonds for conducting propulsion current from each section to the adjacent section, a loop circuit for each section including the two rails of the section in multiple and an impedance, and a second impedance for each such circuit for preventing the flow of propulsion current through such first impedances.

In testimony whereof I affix my signature.

HERMAN G. BLOSSER.
